BRASSIÈRE

Claribel Moore, Washington, D. C.

Application October 5, 1935, Serial No. 43,793

8 Claims. (Cl. 2—42)

This invention relates to improvements in brassières, and contemplates a brassière so constructed as to perfectly shield the bust from view under all circumstances and conditions, even when stooping or bending forward, which, when facing others, has heretofore been embarrassing, to support the bust in a firm, immovable position, exact where nature intended it to be, to greatly reduce in appearance the size of large busts, to restore broken-down or sagging busts to their original, youthful firmness and resiliency, to promote deeper breathing by removing the weight and pressure of large, sagging busts from the diaphragm, and to prevent irritation from chafing, rubbing and similar causes by drawing the breasts apart and backward, toward the armpits.

The brassière of the invention comprises a foundation member of proper size and shape to encompass and fit the body of the wearer over the bust, and provided upon its inner surface with pockets or receptacles for separately receiving the breasts, the whole preferably being supported from the shoulders of the wearer by appropriate shoulder straps, and including, as distinctive features, crossed bands, preferably of elastic material, and a tab element connected with the pockets or receptacles and with the crossed bands; the shoulder straps and the crossed bands being provided with adjusting means, all as will be explained hereinafter more fully and finally claimed.

In the accompanying drawings illustrating the invention, in the several figures of which like parts are similarly designated,

Figure 1 is a front or outside view of the improved brassière, and

Fig. 2 is an inside view of same.

Fig. 3 is an enlarged, fragmentary detail view showing the other side of the tab element and attached crossed straps from that illustrated in Fig. 2.

Fig. 4 is an enlarged view of a piece of material appropriately cut to form either of the pockets or receptacles.

Fig. 5 is a view similar to Fig. 4, but illustrating the production of a fold or dart for the purpose of aiding in providing an appropriate contour for the member.

In the embodiment of the invention illustrated in the drawings the brassière is shown in the form best suited to women of full figure and, although it is for use by such women that the brassière is primarily adapted, it has characteristics which will appeal to all women for whom

such a garment is a desired adjunct of dress, and may be so designed, cut and fitted as to adapt it to the figures of women of various sizes and proportions, as will later be pointed out.

In the form of the invention illustrated, the foundation member of the brassière comprises a front member 1 and similar back members 2 preferably joined to the front member by elastic inserts 3, the back members being provided with complementary parts of fastening devices such as ordinary hooks 4 and eyes 5 by which the foundation member may be secured in position encompassing the body of the wearer over the bust. The brassière is shown as adapted to be fastened in the center of the back, and this is preferred. However, it may be fastened under either arm, or in front, if desired.

The foundation member, instead of being cut low under the arms, as is customary, is cut high, thus providing for shielding of the bust from view when sleeveless dresses are worn, and it is preferably cut low in the back in order that it may not be visible when dresses with low-cut backs are worn.

The elastic inserts 3 are arranged in such positions as to come at the sides of the brassière below the wearer's armpits, and the resiliency provided by their incorporation in the brassière makes it possible to wear the garment tight around the body with perfect comfort and safety and without hindering free expansion of the chest and diaphragm in breathing. The front member 1 is provided adjacent to the center of its upper edge with a dart 6 supplemented by an appropriate number of subjacent horizontal tucks 7 whereby undesired fullness in this part of the garment is eliminated. Also, in order to properly shape and fit the lower portion of the front member, darts 8 arranged substantially symmetrically with respect to the vertical center line of the front member are provided. Furthermore, the lower edge of the member 1 is provided with a small strap 9, preferably of elastic material, and bearing a hook 10 or other fastening device by means of which it may be attached to a girdle or corset to hold the brassière down snugly and thereby prevent any up and down movement of the bust.

The upper and lower edges of the foundation member may be finished in any desired way, as by facing with narrow bias strips, or by binding with either bias or straight seam binding, as indicated at 11, Fig. 2.

To the inner surface of the foundation member are applied two similar pockets or receptacles

12 for separately receiving the breasts, these pockets or receptacles being spaced equidistant from the center of the front portion 1 of the foundation member and being so formed as to provide the desired shape and fullness. Referring now to Figs. 4 and 5, and showing the blank from which these pockets or receptacles may be formed, it will be seen that this blank comprises a piece of material preferably cut 5 upon the bias, as indicated by the arrow *a* and having a part 13 which forms the portion of the receptacle or pocket which contacts with the body of the wearer and underlies the breast, this part 13 having an extension 14 which, when 10 the pocket or receptacle is finished, provides an attaching member or bridle for one of the shoulder straps. Integral with the part 13, and joined thereto upon the fold line 15 is a complementary part 16 which, when it is appropriately 15 secured to the part 13, as will be hereinafter described, provides the means whereby the desired fullness is given to the pocket or receptacle and by means of which the same is attached to the foundation member.

20 The part 13 is adapted to be folded upon the lines *b* to provide a dart or fold 17 which, when the pocket is completed, aids in giving it a proper contour.

After the dart or fold 17 has been formed, the 25 curved edges 18 and 19, and 20 and 21 of the parts 13 and 16, respectively, are stitched and felled together, as indicated at 22, 23, respectively (Fig. 2), to give the desired shape to the pockets or receptacles, and thereafter the edge 30 24 is bound, either with bias seam binding or with narrow strips of material 25, cut bias, to conform to the bias edge 24. The edge 26 of the pocket or receptacle is then stitched, as indicated at 27 to the inside of the foundation member and the parts 14 which have been suitably bound and hemmed, as indicated at 28, are stitched 35 along one edge (the edge 29) to the foundation member, as indicated at 30, thus leaving reverted bends or corner portions 31 of the pockets or receptacles substantially free of the foundation member, except for their connection with their parts 14.

A slide loop 32 is placed upon the part 14 of each of the pockets or receptacles, and the end 40 of each of these parts 14 is brought down and adjustably secured to a slide buckle 33 attached to the foundation member either upon its outer surface, as shown, or upon the inner surface, which latter is preferable. This mode of attachment provides an adjustable bridle for each of the shoulder straps 34 which themselves are made 45 adjustable by loops 35 passing through the members 32 and secured by slide buckles 36, the other ends of the shoulder straps being stitched or otherwise suitably secured to the back members 2, as indicated at 37.

The shoulder straps 34 may be formed either of elastic or inelastic material. When the brassière is to be worn by stout women, or women of 50 very full figure, the use of elastic shoulder straps is advisable, though not necessary, and when it is to be worn by women of regular figure, preferably inelastic shoulder straps are used.

The free corner portions 31 of the pockets or 55 receptacles 12 are connected to the upper corners 38 of a tab element 39, preferably trapezoidal in shape, and to the lower corners 40 of this tab element are applied slide buckles 41 (see Fig. 3), in which are adjustably engaged elastic bands 42, 60 crossed as indicated, and having their upper ends

fastened at 43 to the members 14. The other ends of these elastic bands may be provided with complementary fastening devices such as a hook 44 and eye 44', so they may be passed around the body of the wearer and fastened at the back, or they may be attached to the complementary meeting edges of the back members 2 and thus passed around the body of the wearer and secured when the brassière is applied or put on.

By providing for adjustment of the bands 42 10 by means of the slide buckles 41, any desired tension may be placed upon the tab element 39 and hence upon the free corner portions 31 of the pockets or receptacles 12, thereby ensuring the application of the desired pressure of the 15 bands 38 upon the bust to prevent the breasts from slipping from the pockets or receptacles 12 when the wearer stoops or bends forward.

Moreover, these portions of the parts 14 which 20 extend upwardly from the corner portions 31 and merge into the bridles provide elements which partially overlie the breasts no matter what the position assumed by the wearer may be, and hence conceal the breasts from view.

In order that the portion of the front member 25 1 which overlies the pockets or receptacles 12 may be suitably shaped, darts 45 are provided, which, in combination with the appropriate shaping of the pockets or receptacles 12, as explained, tend to produce a snug and comfortable fit of the 30 brassière upon the bust.

As hereinbefore stated, the brassière as illustrated in the drawings is in a form suitable for a stout person, and is relatively deep from top to bottom. This necessitates a plurality of fastening devices at the meeting edges of its back members 2. However, if desired, the brassière may be so shaped by tapering it from its central front portion to its back edges that only one or two fastening devices are required for the meeting 40 edges.

From the foregoing it will be seen that when the brassière is worn, the foundation member thereof is supported upon the body of the wearer not only by its proper fit augmented by the elastic 45 inserts 3, but also by the shoulder straps 34, the adjustment of which latter may be appropriately made by means of the slide buckles 33 and 36, and that when the bust is supported in the pockets or receptacles 12, the breasts will be held in proper position by the brassière. Furthermore, the crossed straps 42 are so arranged as to exert pressure upon the breasts to force and hold them away from the center and keep them confined within the receptacles or pockets 12, and the tab 50 element 39 not only acts as a means for proper adjustment of the bands 42, but acts, in combination with these bands as a support for the free reverted bends or corner portions 31 of the pockets or receptacles, and thus serves to hold the upwardly extended portions of the parts 14 in proper 55 position to prevent embarrassing exposure at all times, and particularly when stooping or bending.

Furthermore, the arrangement of the bands 42 and tab element 39 is such that the tab element 60 is always held firmly against the chest of the wearer, and the portions 31 of receptacles 12 and their adjacent parts are maintained in proper, desired adjustment.

Various changes are contemplated as within 70 the spirit of the invention and the scope of the following claims.

What I claim is:—

1. In a brassière, a foundation member appropriately fitted to and adapted to encompass the 75

body of the wearer over the bust, appropriately shaped pockets carried upon the interior of the foundation member and adapted to separately receive the breasts, and bands attached to the foundation member upon the interior thereof and arranged in crossed relation adjacent to the bust, said bands serving to confine the breasts within said pockets.

2. In a brassière, a foundation member appropriately fitted to and adapted to encompass the body of the wearer over the bust, appropriately shaped pockets carried upon the interior of the foundation member and adapted to separately receive the breasts, said pockets provided with parts extending outwardly therefrom and secured to said foundation member, and bands attached to said outwardly extending parts and arranged in crossed relation adjacent to the bust, said bands serving to confine the breasts within said pockets.

20 3. In a brassière, a foundation member appropriately fitted to and adapted to encompass the body of the wearer over the bust, appropriately shaped pockets carried upon the interior of the foundation member and adapted to separately receive the breasts, a tab member attached to said pockets and connecting portions thereof across the front of the brassière, and bands attached to the foundation member upon the interior thereof and to said tab member, said bands arranged in crossed relation adjacent to the bust, and serving to confine the breasts within said pockets.

25 4. In a brassière, a foundation member appropriately fitted to and adapted to encompass the body of the wearer over the bust, appropriately shaped pockets carried upon the interior of the foundation member and adapted to separately receive the breasts, bands attached to the foundation member upon the interior thereof and arranged in crossed relation adjacent to the bust, and means for securing said bands at the back of the wearer, said bands serving to confine the breasts within said pockets.

30 5. In a brassière, a foundation member appropriately fitted to and adapted to encompass the body of the wearer over the bust, appropriately shaped pockets carried upon the interior of the foundation member and adapted to separately receive the breasts, said pockets provided with parts extending outwardly therefrom, means for adjustably connecting the ends of said parts with said foundation member to furnish bridles for attachment of shoulder straps, and bands attached

to said outwardly extending parts and arranged in crossed relation adjacent to the bust, said bands serving to confine the breasts within said pockets.

6. In a brassière, a foundation member appropriately fitted to and adapted to encompass the body of the wearer over the bust, appropriately shaped pockets carried upon the interior of the foundation member and adapted to separately receive the breasts, a tab member attached to said pockets and connecting portions thereof across the front of the brassière, and bands attached to the foundation member upon the interior thereof and arranged in crossed relation adjacent to the bust, said bands adjustably secured to said tab member and serving to maintain said tab member substantially flat against the wearer's body between the breasts and to confine the breasts within said pockets.

10 7. In a brassière, a foundation member appropriately fitted to and adapted to encompass the body of the wearer over the bust, appropriately shaped pockets carried upon the interior of the foundation member and adapted to separately receive the breasts, said pockets having relatively free corner portions adjacent to the center of the front of the brassière, a tab member attached to said pockets and connecting the free corner portions thereof across the front of the brassière, and bands attached to the foundation member upon the interior thereof and to said tab member, said bands arranged in crossed relation adjacent to the bust, and serving to confine the breasts within said pockets.

15 8. In a brassière, a foundation member appropriately fitted to and adapted to encompass the body of the wearer over the bust, appropriately shaped pockets carried upon the interior of the foundation member and adapted to separately receive the breasts, said pockets provided with members extending upwardly from the portions thereof adjacent to the center of the garment and furnishing parts overlying the breasts and tending to press them laterally from the center of the body, a tab member connected with the said parts of the pockets, and bands attached to said upwardly extended members and to said tab member and arranged in crossed relation adjacent to the bust, said bands and said pocket parts serving, respectively, to confine and conceal the breasts within said pockets.
